BOX

Louise A. Smith, Buffalo, N. Y., assignor to F. N. Burt Company, Ltd., Toronto, Ontario, Canada, a corporation of Ontario, Canada

Application February 26, 1931, Serial No. 518,325

1 Claim. (Cl. 206—44)

This invention relates to display devices and particularly to merchandise containers which facilitate the display of the merchandise contained.

5 An object of the invention is to provide a container for merchandise which may readily be converted into a display standard, without removing the merchandise from the container.

10 A feature of the invention resides in a container having a pivoted swinging element upon which the merchandise is mounted and which is adapted when swung in one position to display the merchandise and when in another position to encase the same and act as a closure for the container.

15 Another feature of the invention resides in causing the free edges of the pivoted element to fit snugly with the sides of the container and in reinforcing at least one of said sides to provide extra resiliency whereby the pivoted element is more readily retained in its closed or in its display position.

20 Another feature of the invention resides in adapting the reinforcing element to form a base upon which the container may stand when it is desired to display the contents.

25 Other objects of the invention will in part be obvious and will in part appear hereinafter.

The invention accordingly comprises an article 30 of manufacture possessing the features, properties, and the relation of elements which will be exemplified in the article hereinafter described and the scope of the application of which will be indicated in the claim.

35 A better understanding of the invention may be had by reading the following description together with the accompanying drawing, wherein

Fig. 1 shows the invention with the closure element pivoted in the position to display the contents;

40 Fig. 2 shows the closure element in the reverse position after the box has been completely closed;

Fig. 3 is a sectional view showing structural details of the container; and

45 Fig. 4 is a similar sectional view showing the swinging element in another position.

Referring now to the drawing, a display container is shown having a top 10, sides 11, rear face 12 and bottom 13. The container may be 50 of any suitable material having an appreciable amount of inherent resiliency such as paper, cardboard or the like. As the container is to be used for display purposes, the outside surface may be of a fancy nature and colored so as to be attractive to the eye.

A closure for the container is provided by the element 14 which is centrally pivoted at 15 so as to permit the normally inner surface 16 to be swung into view as in Fig. 1. As this inner surface is adapted for the display of merchandise, it may be covered with some suitable fabric such as velveteen or the like. In the particular embodiment shown, the container is adapted for displaying such articles as a pen and pencil set, and for this purpose retaining means, as for instance, cord loops 17 are provided to mount the merchandise in position on the swinging closure element.

When it is desired to close the box for packing and shipping purposes, the pivoted element 14 is 15 swung into the reverse position as shown in Fig. 2 so that the merchandise is encased within the container. The back of the closure element 14 is preferably decorated similarly to the other outside surfaces of the box 10, 11 and 12.

20 The bottom of the box is provided with a strip 18 of stiffer material than the rest of the box which acts as a base or standard upon which the display device rests. This strip may be glued or otherwise suitably fastened in position.

25 Fig. 3 and Fig. 4 illustrate the closing of the container and the manner in which the closure element is retained in this position. It will be noticed that the closure element 14 is adapted to fit snugly into the opening 20. Obviously, the distance between diagonally opposite edges of the closure element is therefore greater than the width of the opening 20 so when the closure element is in the position shown in Fig. 3 the edges 21 are contacting with the top and bottom of the box. As the closure element is swung still further to the closing position, as shown in Fig. 4, it tends to expand the edge of the box, as at 22, which expansion however is resisted by the resiliency of the container material. When the container is completely closed it is prevented from swinging open for the same reason. To assist further in preventing the closure element from swinging voluntarily, the base reinforcing strip 18 is provided which tends to stiffen one edge of the opening 20. Since the closure element 14 is of substantial thickness the distance between the pivot 15 and the edge 21 is slightly larger than the shortest distance between the pivot 15 and the sides 10 and 13. It is obvious therefore that the reinforcing strip 18 further assists in holding the closure element 14 in the closed or open position. Furthermore, when the display cover 14 is in the position shown in Fig. 1, the frictional drag between the inner edges 21 30

resting against the sides 10 and 13 of the container hold it in an angular position better suited for display purposes.

Although the edges of the closure member 14 may vary in configuration, they are conveniently flat as shown and of substantial width or extent, both of these opposite edge surfaces being similar and positioned at an angle to the general plane of the closure element. Due to this arrangement, these flat edges when the closure member is swung upon its pivot, will engage forcibly against the opposite resilient walls 10 and 13 of the container, thereby effecting a locking or retaining function for retaining the closure member in different adjusted positions. The closure member may thus be secured in one adjusted position in which it functions to close the container opening as in Fig. 2, or in another adjusted position in which the closure member is reversed so as to expose the normally inner surface outwardly in a manner as suggested in Fig. 1. In the Fig. 2 position, the flat edges of the closure member engage against the resilient container walls, so as to retain the member in its fully closed position; in the Fig. 1 position, the corners or edges 21 of the flat edge surface are in engagement with the container walls whereby the closure member may be supported in tilted or inclined position, but said closure member may be forced into position parallel with the outer edges of the container walls so as to be held in this reversed position by engagement of the flat edges with the container walls in a similar manner as described with reference to Fig. 2. Thus the movable closure member or display element may be supported in different positions for display of the merchandise. The relative rigid supporting base 18 attached to the container wall 13 considerably reinforces and rigidifies this wall while the opposite wall 10 is of greater flexibility and resiliency. This arrangement assists in providing a more positive support for the closure member in its display position as seen in Fig. 1. However, there is considerable resiliency in the wall 13 even when reinforced by the base member 18, because of the flexibility provided by the angular juncture between the ends of the side wall 13 and the adjacent ends of the container, as well

as to other portions of the container structure. Therefore, both side walls 10 and 13 will function to secure the resilient frictional retaining engagement with either of the flat edges of the closure member.

It is thus obvious that the invention provides a unique display standard, somewhat resembling a frame for the merchandise rather than a box, but which admirably serves the purpose of a container by merely reversing the position of the closing element upon which the merchandise is mounted. The novel idea of utilizing the resiliency of the base to maintain the closed position of the box is also an exceedingly valuable feature of the invention.

Since certain changes may be made in the above article and different embodiments of the invention could be made without departing from the scope thereof, it is intended that all matters contained in the above description or shown in the accompanying drawing shall be interpreted as illustrative and not in a limiting sense.

It is also to be understood that the following claim is intended to cover all of the generic and specific features of the invention herein described, and all statements of the scope of the invention which, as a matter of language might be said to fall therebetween.

Having described my invention, what I claim as new and desire to secure by Letters Patent is:

A container having an entrance opening and including, in combination, a closure member and article support centrally pivoted for swinging movement into closing position in said opening and into a second position with its inner surface outwardly exposed, said closure member having relatively wide flat opposite edges, and the opposite container walls being resilient and resiliently frictionally engaging said flat edges of the closure member to retain the latter in said positions, and a reinforcing and supporting base attached to one of said walls and positioned at the edge thereof with which the closure edge comes into engagement so as to support the closure member in tilted position.

LOUISE A. SMITH.
